TOTALING DEVICE FOR ADDING MACHINES

Glenn J. Barrett, Grand Rapids, Mich., assignor
to Portable Adding Machine Company, New
York, N. Y.

Application September 3, 1931. Serial No. 561,551

6 Claims. (Cl. 235—60)

My invention relates to improvements in totaling devices for adding machines of the class described hereinafter and its objects are:

First, to provide a total lever operable in two directions, normally retained in a central position, the movement of said lever in one direction setting devices so that the total upon the accumulators may be positioned for printing during the operation of the main operating mechanism, and thereafter the accumulation returned into the accumulators thereafter for a subtotal, and when said lever is moved in the opposite direction, the same total will be positioned for leaving the accumulators at zero position. The former operation is known as a subtotal operation and the latter, as a final total. This briefly is to provide means wherein a movement of said total lever in either direction produces exactly the same result so far as positioning the total for printing is concerned, but when moved in one direction in addition it positions parts so that the accumulators are left clear.

Second, to provide means for forcing the total lever back to normal position at the limit of the movement of the main operating mechanism away from normal position, in order to prevent a possible maloperation of the machine as hereinafter explained and described.

Further objects pertaining to details will appear from the description to follow. The invention is defined and pointed out in the claims.

I have chosen to describe my invention as applied to certain structures of the well-known Corona adding machine, and the several views herewith clearly disclose its principles, in which:

Fig. 1 is a side elevation of my invention as applied to certain cooperating parts of a Corona adding machine, a portion of the main operating mechanism being broken away to disclose the means for forcing a return of the total lever to normal position.

Fig. 2 is a side elevation view of the parts of a Corona adding machine with which my invention cooperates, said parts being in position after moving my total lever in the direction to produce a final total, the operating mechanism being near the forward limit of its movement, showing the means for forcing the total lever (partially in dotted lines) to normal position about to become effective.

Fig. 3 is a detail elevation showing approximately a side elevation of the same parts as in the previous figures, certain details being omitted of the total lever returned to normal position and other parts set to leave the accumulators at zero,

with the operating mechanism at the limit of its forward movement.

Fig. 4 is a detail elevation showing practically the same parts as seen in Fig. 3, with the operating mechanism starting upon its return towards normal position, the accumulator frame just being forced down out of active accumulative position.

Fig. 5 is a detail elevation showing the position of certain parts of said Corona adding machine after depressing the subtotal button, and without setting said parts for leaving the accumulators at zero position.

Fig. 6 is a detail of the cam 18 and cooperating pin for relieving the positioning member to central normal position.

My invention is applicable to any key set adding and listing machine. This machine is exemplified in the well known Corona adding machine such as appears in various patents of mine and particularly in United States Patent No. 1,681,567, issued August 21, 1928, for Accumulator control means for adding machines. These machines contain the following well known mechanical features or elements:

Adding actuators having a reciprocating movement.

Numeral type adapted to move in synchrony with said adding actuators and arranged in denote columns to correspond and coact with said actuators.

Rotatable accumulators mounted in an oscillating frame adapted to go into and out of mesh or active relation with said actuators.

A main operating mechanism having a reciprocating movement for actuating the various mechanisms of said adding machine, controlled by the manual setting of controlling keys, for printing an item during the forward movement thereof, and adding same into said accumulators upon the return thereof to normal position, said operation being known as an adding operation, wherein during the first portion of said operation said accumulators are maintained out of mesh or active relation with said accumulators, and during the second portion of said operation when said main operating mechanism is returning toward normal position, said accumulators are maintained in mesh with said accumulators.

A settable non-add means, the function of which is to maintain said accumulators out of mesh with said actuators during the return of said operating mechanism toward normal position.

A total positioning means upon the operation of which prior to the operation of said main op-

erating mechanism, said accumulators are main-
tained in mesh with said actuators during the
movement of said main operating mechanism,
thereby rotating said accumulators back to zero
5 position and positioning type respectively in
printing position to correspond with the accumu-
lation upon said accumulators. In machines of
this class, when said non-add means is positioned
10 in conjunction with the positioning of said total
means, the operation of the main operating mech-
anism presents type representing the total ac-
cumulation upon the accumulators, and after-
wards forces said accumulators out of mesh or
15 active relation with their actuators while at the
zero position to which they were rotated when
presenting said type representing said total, the
latter operation being known in the art as a final
total operation. The operation of said total
20 means alone produces what is known as a sub-
total operation, the accumulation being returned
to the respective accumulators as same are main-
tained in mesh with their actuators during the
complete cycle of operation of said main operating
25 mechanism.

25 The parts will be identified by their numerals
of reference which are the same in all the views.

In order to understand the application of my
invention to the Corona adding machine, I will
30 now describe certain features of the latter which
cooperate with my invention.

35 The dotted lines in Fig. 1 disclose the outlines
of the settable numeral keys of the Corona adding
machine, together with the platen and printing
mechanism which, however, form no part of
my invention. 1 is the main operating handle
40 having a reciprocatory movement. 2 is an oscil-
lating plate to which said handle 1 is attached.
3 is the pivot or shaft upon which it oscillates and
thus reciprocates. 4 is a vibrating accumulator
frame pivoted at 5. This frame, it will be under-
45 stood, contains the rotary accumulators of the
adding machine. 6 is a roller mounted upon the
pivoted arm 7 and carried by said frame 4 pivoted
at 41. 21 is a cam surface on the plate 2 which
50 contacts with the roller 6 carried by arm 7 during
an early portion of the forward movement of the
handle away from normal position. This con-
tact of cam 21 with roller 6 forces the accumu-
lator frame out of normal active position for ac-
55 cumulating. During the early portion of the re-
turn of said operating handle 1 toward normal
position this roller 6 is forced toward the left
and the accumulator frame is allowed to return
to normal active position by virtue of a spring,
60 not shown in the accompanying illustrations.
Such is the usual construction.

65 8 is a total positioning plate pivoted at 9 to
the main frame of the adding machine, a portion
of which appears in dotted lines. When the
lower portion of this oscillating plate 8 is swung
back or toward the right, the stud 81 on a de-
pendent arm 82 thereof contacts with the arm
7 causing the roller to take the position shown
in Fig. 2 so that it is not contacted by the cam
face 21 and under this condition the accumulator
frame is allowed to remain in active normal posi-
75 tion.

79 It will be understood that when the accumula-
tor frame 4 is in normal position or position shown
in Fig. 1, the accumulators carried by said accumu-
lator frame are in active accumulative posi-
tion with relation to the adding actuators of the
adding machine. When the accumulator frame
75 4 is in position shown in Fig. 4, with the roller
6 bearing against the arc of the cam 21 on the

periphery of the plate 2, the accumulator frame
is in inactive accumulative position with refer-
ence to the adding actuators of the adding ma-
chine.

80 In the Corona adding machine a subtotal is
obtained by first causing the lower portion 82
of the total positionable member 8 to swing toward
the right, or toward the rear of the machine
and then starting the main operating mech-
anism, after which a pin 83 in the plate 8 (Fig. 5) is
85 engaged by the circular plate 22 carried by the
member 2 and the plate 8 is held in position shown
in Fig. 5 until the operating handle nears the
end of its forward movement or position shown
in Fig. 2. A slightly further movement of the
90 plate 2 (Fig. 2), in the direction of the arrow,
will cause the pin 83 to drop off the plate 22 when
the plate 8 will return to normal position shown
in Fig. 1 under the tension of the centralizing
spring 10 shown in Fig. 1. The totalizer wheels
95 are swung to engagement by the usual spring
means indicated above but not illustrated.

100 To obtain a final total wherein the accumu-
lators are left at zero position, the said plate 8
is positioned just as in obtaining a subtotal, but in
addition certain other parts are positioned so that
immediately after the plate 8 returns to normal
position after being in the position shown in Fig.
1, and upon the early return of the main operat-
ing mechanism toward normal position, the ac-
cumulator frame is forced out of active accumu-
lative position as shown in Fig. 4. In the Corona
105 adding machine this additional mechanism con-
stitutes a non-add positionable mechanism and
consists of the latchable key stem 11, the non-add
pawl 12, and the yielding positioning spring 13.
Normally the end 121 of the pawl 12 is out of the
path of travel of the pin 23; however, when the
110 non-add parts are positioned as in Fig. 3 the end
121 of the pawl 12 is lifted into the path of travel
115 of the pin 23 shown in Fig. 3 as being in its ex-
treme position, the operating mechanism being
at the limit of its forward movement. During
the early return of the operating mechanism, this
pin 23 contacts with the end 121 of pawl 12, with
120 the parts positioned as shown in Fig. 4. The pawl
12 contacts with a pin 84 in the plate 8 causing
the latter to swing in the direction of the arrow
(see Fig. 3) until the pin 85 unlatches the key
125 stem 11 and the latter returns to normal position
as shown in Fig. 4, said accumulator frame 4
being forced out of active position by reason of
contact of cam 89 carried by said total positioning
plate 8, against stud 42 in said accumulator
130 frame 4, when said plate 8 swings toward the left
actuated by said pawl 12 against said stud 84.
Thus the accumulator frame is maintained out
of active accumulation position during a return
or adding movement of said main operating
135 mechanism.

140 A portion of my invention consists of a finger
key lever 14 suitably mounted to move in two
directions, and normally held in a central posi-
tion. I have shown this finger key 14 pivoted
at 15 upon the side plate of the adding machine
as shown in Fig. 1. 16 is a centralizing spring for
this finger key 14 which retains the latter in a
central normal position. 141 is a button carried
on the upper portion of the key 14, the depression
145 of which forces the upper portion of said key
rearwardly. 142 is another button carried upon
a forward portion of the key 14, the depression
of which button forces said key to rock in the op-
posite direction to that when moved by said but-
ton 141. 143 is a contact portion of key 14 which

- is adapted to contact with the pin 86 in the plate 8. When the button 141 is depressed this contact portion 143 contacts with said pin 86 and a continued movement of said button 141 causes said plate 8 to swing to the position shown in Fig. 2. This renders the roller 6 inoperative as explained and the accumulators are left in active accumulative position during a movement of the main operating mechanism to position shown in Fig. 2. It is understood that in machines of the class of the Corona, type for printing a total are positioned by a backward rotation of the accumulators, rotated by their respective adding accumulators to the zero position.
- 15 Parts above described for a non-add operation, forcing the accumulators out of active accumulative position, are also positioned by the movement of said button 141 to position shown in Fig. 2, as I will now describe. 17 is a lever pivoted at 9, said lever having an angular lateral contact ear 171. The movement of the key 14 causes the contact portion 143 to contact against said ear 171 causing the forward end 172 of said lever 17 to swing downwardly contacting with pin 111 (see dotted lines Fig. 2) in the key stem 11 forcing the latter and its cooperating parts to the position shown in Fig. 2. Upon release of said button 141 and after starting the main operating mechanism, said key stem 11 remains in latched position shown in Fig. 3, said button 141 and said lever 17 return to normal position shown in the same figure. The operation of the adding machine after setting parts as just described, produces a final total operation leaving the accumulators clear.
- When it is desired to print a subtotal returning the accumulation back into the accumulators, this total positioning plate 8 is moved in the same direction as by the contact of 143 against the pin 86 as previously described but by means of contact of the cam surface 144 upon the plate 14 against the stud 87 on the plate 8. In order to accomplish this movement, the button 142 is depressed which swings the key 14 in the opposite direction from a depression of the button 141, but owing to the contact of the cam 144 against stud 87, the plate 8 is forced to move in the same identical direction and amount of travel as when forced by the contact of 143 against the pin 86. In the operation of the button 142 however, the plate 8 is made to swing without positioning any of the non-add parts, 11, 12, 13, etc. Thus it will be seen that my invention provides for a member movable in two distinct directions away from a central normal position. When moved in one direction, it positions parts for printing a total, and also for forcing the accumulators out of active accumulative position during the return of the operating mechanism for the final total; and when moved in the opposite direction positions the same parts for printing the subtotal; that is, the same number which is returned to the accumulator, but does not position the parts for forcing the accumulators out of active accumulative position as in the final total. The said total positioning parts move in the same direction each time when actuated by the key 14 moving in opposite directions. This avoids the use of two keys operating in the same direction and possible confusion by unintentional operation of both said keys.
- Another feature of my invention is to provide means for forcing primarily the total positioning member 8 back to normal central position at the end of the forward movement of the operating
- mechanism, and with it of course the key 14. Otherwise a maloperation of the machine might result if said key 14 were held in depressed position during the early return of the operating mechanism, as this would prevent the operation of the non-add feature, or feature to force the accumulators out of active accumulative position in order to leave them at zero position. The restoration of total plate 8 by pawl 12 is effective in total taking operations only, and for that reason another positive restoring means is provided for plate 8 in sub-total cycles.
- This feature of my invention includes a means carried by the main operating mechanism adapted to contact with said total positioning means when the latter is out of normal position or when the latter is in total printing position, which I will now describe. I provide a cam piece 18 rigidly attached to the rear side of the plate 2 of the main operating mechanism (Fig. 1), showing a portion of said plate 8 broken away to expose said cam plate. A pin 88 is positioned on said total positioning member 8 normally out of the path of travel of this cam plate 18. However, when said positioning member 8 is positioned as described and shown in Fig. 2, said pin 88 comes into the path of travel of the cam plate 18 and is contacted by the latter when the operating mechanism nears the limit of its forward movement, and said positioning member 8 is forced back to normal position when the operating mechanism reaches the limit of its forward movement (see Fig. 6). If said key 14 be held in depressed position, the contact portion 143 being against the pin 86, when said positioning member 8 is forced back to normal position, said key must also be forced out of operative position. Fig. 2 shows the cam 18 in dotted lines just beginning to contact with the pin 88. Fig. 6 shows the cam 18 at the limit of its motion, having forced the pin 88 back to central normal position. It will be readily understood how a continued movement of said cam 18 will force said pin 87 down, and reposition said positioning member 8.
- While I have shown my invention applied to the Corona adding machine main operating and totaling mechanisms, the same may be applied to any standard adding machine having equivalent parts and actions.
- I desire to claim the specific structure illustrated and also the invention broadly as pointed out in the appended claims.
- Having thus described my invention, what I claim as new and desire to secure by Letters Patent is:
1. In an adding machine of the class described having the elements as specified, and embracing a total positioning means, a non-add conditioning means, and a main operating mechanism, the combination of a manually operable pivoted member adapted to swing in either direction away from a central normal position, a yielding means for normally maintaining said pivoted member in normal position, finger keys or buttons carried upon said pivoted member at opposite positions from a vertical line through the pivotal point of said pivoted member, means for moving the total positioning means of said adding machine in the same direction by movements of said pivoted member in either direction away from said central normal position, consisting of contact points carried by said total positioning means, differentially arranged, contact connections from said pivoted member to cooperate with said contact points upon said total positioning means

- respectively one of which contact points on said pivoted member being a cam, means for setting the non-add means of said adding machine when moving said pivoted means in one direction from 5 said normal central position, and means for forcing said pivoted member back to normal central position when said operating mechanism nears the limit of its forward movement consisting of a cam actuated by said main operating mechanism, a pin or stud in said total positioning means 10 normally out of the path of travel of said cam, but positioned in the path of travel of said cam when said total means is positioned for the printing of a total.
- 15 2. In an adding machine of the class described having the elements as specified, and embracing a total positioning means, a non-add conditioning means, and a main operating mechanism, the combination of a manually operable pivoted member 20 adapted to swing in either direction away from a central normal position, a yielding means for normally maintaining said pivoted member in normal position, finger keys carried upon said pivoted member so positioned that a depression 25 of each alternately causes said pivoted member to swing in opposite directions, means for moving the total positioning means of said adding machine in the same direction by movements of said pivoted member in opposite directions away 30 from said central normal position, consisting of contact points upon said total positioning means to contact and cooperate with contact points upon said pivoted member, one of said contact points on said pivoted member being in the form of a 35 cam, means for setting the non-add means of said adding machine when moving said pivoted member in one direction away from said central normal position, and means for forcing said pivoted member back to normal position when said 40 main operating mechanism nears the limit of its forward movement away from normal position consisting of an oscillating contact member carried by said main operating mechanism and a contact portion on said total means to cooperate 45 with said contact member carried by said main operating mechanism normally out of the path of travel of said contact member but movable into said path of travel when said total means is in position to produce a total during the operation 50 of said main operating mechanism.
3. In an adding machine of the class described having the elements as specified, and embracing a total positioning means, a non-add conditioning means, and a main operating mechanism, the 55 combination of a manually operable pivoted member adapted to move in either direction away from a central normal position, a yielding means for normally maintaining said pivoted member in said central normal position, suitable finger keys 60 mounted upon said pivoted member for moving the same in opposite directions respectively away from normal position, contact means between said pivoted member and the total positioning means of said adding machine, whereby a movement of said pivoted member in either direction causes said total means to move in the same direction, means for setting the said non-add means in operative position with relation to the main operating mechanism when moving said pivoted member in 65 one direction away from said normal position, and means for forcing said pivoted member back to 70
- normal position when said main operating mechanism nears the limit of its forward movement consisting of a contact means carried by said main operating mechanism and connections to said total positioning means when the latter is in position for causing said main operating mechanism to present for printing, type representing the accumulation upon said accumulators. 80
4. In an adding machine of the class described having the elements as specified, and embracing a total positioning means, a non-add conditioning means, and a main operating mechanism, the combination of a manually operable movable member adapted to move in either direction away 85 from a central normal position, a yielding means for normally maintaining said manually movable member in a central normal position, contact means between said manually operable member and the total positioning means of said adding machine, whereby a movement of the former in either direction away from said normal position, moves said total means in the same direction, means for setting the settable non-add means of said adding machine by a movement of said manually operable movable member in one direction, 90 and means actuated by the main operating mechanism of said adding machine for forcing said total positioning means and said manually operable movable member back to normal position when said main operating mechanism nears the 95 limit of its forward movement away from normal position. 100
5. In an adding machine of the class described having the elements as specified, and embracing a total positioning means, a non-add conditioning 110 means, and a main operating mechanism, the combination of a manually operable movable member adapted to move in either direction away from a central normal position, a yielding means for normally maintaining said manually operable 115 member in said normal position, suitable connections between said manually operable member and the total positioning means of said adding machine whereby a movement of said manually operable member in either direction away from 120 said normal position moves said total positioning means in the same direction, and means for setting the non-add means of said adding machine in operative position with relation to said main operating mechanism actuated by the movement 125 of said manually operable member in one direction. 130
6. In an adding machine of the class described having the elements as specified, and embracing a total positioning means, a non-add conditioning 130 means, and a main operating mechanism, the combination of a manually operable movable member adapted to move in two different directions, suitable connections between said manually operable member and the total positioning means of said adding machine whereby a movement of said manually operable member in either of said two directions, moves said total positioning means in the same direction, and means connected to said manually operable member for setting the non-add means of said adding machine in operative position with relation to said main operating mechanism, when said manually operable member is moved in one of said directions. 140

GLENN J. BARRETT.
